The ornamental design for a tracking device, as shown and described.

DESCRIPTION

FIG. 1 is a front perspective view of an embodiment of a tracking device showing the new design;

FIG. 2 is a rear perspective view of the embodiment of FIG. 1 showing the new design;

FIG. 3 is a rear view of the embodiment of FIG. 1;

FIG. 4 is a front view of the embodiment of FIG. 1;

FIG. 5 is a left side view of the embodiment of FIG. 1;

FIG. 6 is a right side view of the embodiment of FIG. 1;

FIG. 7 is a top view of the embodiment of FIG. 1; and,

FIG. 8 is a bottom view of the embodiment of FIG. 1.

The broken lines represent portions of the article that form no part of the claim.

The trademark MARCO in FIGS. 2 and 3 is owned by Appereo IoT, LLC.
